BAILER

Elmer R. Smith, Long Beach, Calif., assignor,
by mesne assignments, to Paul Cavins, Long
Beach, Calif.

Application May 23, 1932, Serial No. 613,105

12 Claims. (Cl. 166—19)

This invention relates to a bailer and particularly pertains to a hydraulic differential or hydrostatic bailer to be used in withdrawing extraneous matter from a remote area of a body 5 of fluid.

In various projects, such as in the drilling of oil wells, the removal of material from tanks, storage vessels or the like, in which there is an accumulated body of liquid or fluids, it often 10 becomes necessary to remove extraneous matter such as debris, sand, mud, and the like, or to recover objects such as lost or broken parts of apparatus, and it is the principal object of the 15 present invention to provide a bailer structure which will operate by hydrostatic action to attain the aforementioned results.

The present invention contemplates the provision of a valve assembly structure carrying a barrel section and supported by collapsible jars 20 and a supporting cable whereby the device may be lowered into a body of fluid and may be controlled in this remote position to be rendered operative under the hydrostatic head of the liquid or mixed fluid within which it is submerged, 25 and which will at that time create a surge into the barrel structure to cause the liquid or mixed fluids and extraneous matter suspended therein to be carried into the barrel structure and there held while the device is removed from the body 30 of liquid and until the device is manipulated to permit the fluids and extraneous matter to be discharged therefrom.

The invention is illustrated by way of example in the accompanying drawings, in which:

35 Figure 1 is a view in side elevation with parts broken away, showing the assembled structure with which the present invention is concerned.

Fig. 2 is an enlarged fragmentary view in section and elevation showing the upper tubular 40 section.

Fig. 3 is an enlarged view in vertical section and elevation showing the valve assembly and the details of construction of the various elements thereof.

45 Fig. 4 is an enlarged view in vertical section showing the barrel section.

Fig. 5 is a view in transverse section through the valve section as seen on the line 5—5 of Fig. 3.

50 Fig. 6 is a view in transverse section through the valve unit as seen on the line 6—6 of Fig. 3.

Fig. 7 is a view in section and elevation showing the socket structure in which the lower end of the barrel is positioned when the material is 55 to be discharged from the bailer, a fragmentary

portion of the barrel being indicated within the socket.

Referring more particularly to the drawings 10 indicates a drill supporting cable from which a jar 11 is suspended. This jar includes the upper member 12 and a lower member 13 attached thereto, but connected in such a manner as to permit a suitable amount of lost motion in connection therewith. The lower end of the member 13 of the jar is a threaded element connect- 10 ing with the upper tube unit 14. This unit is shown in detail in Fig. 2 of the drawings. Disposed beneath the tube unit 14 and in threaded connection therewith is the valve assembly 15, the details of which are shown more clearly in 15 Fig. 3 of the drawings. The lower end of the valve assembly is formed with a threaded connection attaching it to a bottom section or barrel unit 16, the construction of which is shown in detail in Fig. 4 of the drawings. The barrel unit 20 16 may be of any desired length, and it is the object of the present invention to provide suitable operating means whereby the barrel unit may be filled with liquids, fluids and extraneous solid material by hydrostatic action when the 25 device is manipulated at the bottom of a well shaft or at a desired point in any body of fluids. The barrel unit includes a barrel defining what is known in the art as a sand chamber, for the reception of liquids and materials, as discussed 30 above.

The top section 14 as shown particularly in Fig. 2 of the drawings is formed with an upper threaded end 17 carried as part of a head 18. This head is externally threaded at 19 to receive a tube 20. The tube is of uniform diameter with the outside diameter of the head 18. The head 18 is of relatively short length as compared to the tube and is formed with a central bore 21 opening outwardly at its lower end and 40 there internally threaded at 22 to receive a valve seat bushing 23. The bushing has a central passageway 24 establishing communication between the exterior of the head through port 25 and a fluid release tube 26 which is threaded 45 into the lower end of the bushing and extends longitudinally of the tube 20 and to a desired depth therein for a purpose which will be hereinafter described. Mounted upon the upper end of the bushing 23 is a release valve ball 27 held 50 in position by a spring 28 to normally close the upper end of the bushing. The spring 28 is seated within the bore 21 of the head 18. The lower internally threaded end of the tube 26 receives the upper externally threaded connec-

tion 29' of the top of substitute 29. A shoulder 30 is formed on the top substitute and faces downwardly. This shoulder is formed by a portion 31 of the substitute which is of reduced 5 diameter as compared to the body of the member 29, and which reduced portion telescopes into the upwardly opening end of the outer valve shell or valve section 32. The limit of telescoping action is established when the end face 33 10 of the valve shell 32 abuts against the shoulder 30 of the top substitute 29, as will be hereinafter described. The lower end of the top substitute 29 is internally threaded as indicated at 34 to receive the externally threaded portion of a tubular stem 35 formed as an extension of the tubular valve sleeve element 36. The tubular stem 35 terminates at its lower end with a shoulder 37 which normally abuts against a shoulder 38 15 formed in the inner wall of the shell 32. The shoulder 38 occurs at the lower face of an annular internal collar 39 formed integral with the shell 32, and which collar portion has a shoulder 40 at its upper edge to provide a seat against which an expansion spring 41 may rest. This 20 spring circumscribes the tubular stem 35 and is disposed within an annular space 42 occurring between the outer circumference of the stem 35 and the inner circumference of the shell 32. Due to the expansive action of the spring the shoulders 30 and 33 will normally be spaced apart, and the shoulders 37 and 38 will normally be held in contact. The body portion 36 of the stem 35 extends downwardly within the shell 32 a considerable distance below the shoulder 38 25 constituting a valve sleeve. The outside diameter of the valve sleeve does not fit snugly within the shell but forms a longitudinal passageway 43 therewith through which fluids may vent under certain conditions to be hereinafter described.

40 The lower end of the valve sleeve body is internally threaded to receive a valve member 44 which is provided with a relatively narrow central passageway 45 terminating at its upper end 45 in a valve seat 44', and a relatively wide central passageway 46 below passage 45 and forming a continuation thereof. The outer diameter of the valve body 44 is flush with the outer diameter of the valve sleeve. A conical valve member 47 normally rests against the valve seat 44' in the passageway 45 and closes the same.

50 The upper end of the valve member 47 is reduced in diameter and forms a cylindrical extension 48 which receives packing cups 49 and 55 held in position by a tubular screw 51 extending downwardly into a threaded bore 52 in the extension 48 of the valve. A central bypass port 53 extending throughout the length of extension 48 and screw 51 opens outwardly of 60 the valve 47 below that portion of the valve which is adapted to contact the valve seat, and at its upper end opens into cylinder 54 at the uppermost portion of screw 51 whereby cylinder 54 is in communication with the passageway through the valve seat 44' during all times that the valve is closed. The extension 48 of the valve 47, its packings, and screw 51, are reciprocably positioned within a cushion cylinder 54. Cylinder 54 is formed on its outside with a 65 plurality of ribs 55 which contact with the circumscribing side wall of the valve sleeve 36 and guide the cylinder while permitting fluid to pass upwardly around the cylinder and between the webs into the central passageway 56 of the tubular extension 35 of the valve sleeve, and from

70 thence upwardly through the extension of this central passageway in the top substitute 29. The valve 47 is provided with the spring 57 positioned within cylinder 54 and by which the valve may be held normally seated. The valve 47 is formed 75 with a downwardly extending lift pin 58 which projects through the opening formed by passageways 45 and 46. As the valve structure moves to its lower position it encounters a valve opening projection 59 carried by a web 60 occurring 10 at the upper end of a lower substitute 61. This substitute is externally threaded at its upper end to engage internal threads formed at the lower end of the shell 32, and in this manner the valve opening projection will stand in the path of 15 travel of lift pin 58 and will cause the valve to remain stationary as its seat continues downwardly and moves away from it.

10 The lower end of the substitute 61 is externally threaded to be connected to the upper end 20 of the barrel 62 of the lower barrel unit 16. This unit is shown in detail in Fig. 4 of the drawings where it will be seen that the barrel 61 is tubular in formation, being internally threaded at its lower end to receive a shoe 63, shown 25 in Fig. 4 of the drawings, as being tubular in shape and having a bottom opening 64 as well as side perforations 65. For purposes of rotating this shoe grooves 65' are formed in its side walls near its lower end. Near the upper end of the 30 shoe there is formed a valve seat 66 upon which a flapper valve 67 is normally seated. The upper end of the shoe is in the shape of a tubular sleeve 68 which telescopes within the lower end of the barrel 61 and is formed with a port 69 35 through its side wall which may be moved to register with a port 70 through the side wall of the barrel when it is desired to unload the barrel.

40 It will be understood that at times when different materials are to be recovered by the device 40 the shape and size of the shoe may be changed without departing from the spirit of the invention as described.

45 When the shoe is to be rotated in order to bring the ports 69 and 70 into register, the shoe may be placed in engaged relation to the discharge fitting 71. This fitting is normally fastened at some convenient place upon the floor of the derrick. The device comprises a fastening plate 72 and an upwardly extending cup 73 having internal ribs or keys 65 registering with the slotted grooves 65' in the shoe. It will be evident that after the shoe has been fitted into the structure the barrel 61 may be rotated while the shoe is held stationary and until the ports 69 and 70 register.

50 In operation the device is assembled as shown in the drawings after which it may be lowered within a body of fluid until the shoe 62 comes to rest at the bottom of the well bore, shaft, 60 vessel or body of fluid, or in contact with an artificial obstruction purposely placed in an obstructing position. The cable 10 and the tool are then caused to be lowered further and in so doing the weight of the upper section 14 will 65 cause the tubular stem 35 to continue to move downwardly through the liquid while the barrel 16 and the valve shell 32 remain stationary. As the barrel structure 61 moves downwardly through the fluid the liquid and mixed fluids will force 70 their way upwardly through the opening 63 in the shoe 62 and through the holes 64. The hydrostatic pressure of these fluids will raise the flapper valve 67 and cause the fluid to travel upwardly within the barrel 16 until it reaches 75

the valve structure comprising the valve seat 44' and the valve member 47. It is, of course, assumed that at this time the valve structure will also be submerged below the level of the fluid 5 within the well bore, or the like. The hydrostatic pressure of these fluids will cause a certain amount of fluid to pass upwardly through the duct 53 in the center of the valve member 47 and then into the cylinder 54. In this condition the valve 47 will be substantially balanced so that there will be substantially equal hydrostatic pressure on both sides of the valve holding the valve onto its seat. When the upper sections 14 and 13 continue to be lowered with relation to the shell 32 and against the compression of the spring 41, the valve member 47 with its seat will move downwardly until the lift pin 57 encounters the member 58, after which the valve will be substantially stationary, thus causing the 20 valve seat 44' to move downwardly and to open the upper end of the valve at which time the hydrostatic pressure of the fluids will be released causing them to pass upwardly along the passageway around the cylinder 54 and between the 25 guiding ribs 55 and then into the central bore 56 of the tubular stem 35, after which the fluid under its hydrostatic pressure will rise to a suitable level in the upper section 14 and around the fluid release tube 26. The fluid moving upwardly through hydrostatic pressure will tend to displace and depress the air entrapped in the upper end of the top section 14 and around the escape tube 26. Excessive pressure will force the fluid upwardly into the escape tube and 30 through the passage 24, thereafter lifting the ball valve 27 permitting this fluid to vent through the port 25 when a condition arises such as to create a lesser hydrostatic pressure of fluid surrounding the top section 14 than might at the moment exist within this section. When the tool 35 has been thus filled it is then lifted. This will cause the tubular stem 35 to be drawn upwardly with the upper substitute 29 until the shoulders 37 and 38 of the valve member and shell 35, respectively, have moved into a contacting position. As this is accomplished, the valve 47 with its lifting pin 57 will be raised from the obstruction 58 so that the valve 47 may be moved onto its seat by the expansion spring 75 which is housed within the cylinder 54.

It will of course be understood that the flapper valve 67 has closed entrapping all of the fluid which passed upwardly into the barrel structure 16 and through the floating valve to the top section 14. As the tool is raised from the depth of contact with the material which has been entrapped, the air pressure of the annular area of the outer wall of the escape tube 26 and the inner wall of the top tube 20 will act in conjunction with the expansion spring 28 to force the ball valve 27 onto its seat and prevent the escape of fluid, gas, or air which might be in the act of expanding within the escape tube. The tool may then be brought to rest above the floor of 65 the derrick at which time the shoe 62 is properly positioned within the discharge fitting 11. The barrel 16 may then be rotated with relation to the tubular sleeve 68 so that the ports 69 and 70 will register in an opened position. This will 70 permit the entrapped fluid and material associated with it to be discharged from the tool, after which the barrel 16 and the tubular member 68 may be rotated again to close the ports and place the device in condition for further use.

75 Attention is directed to the fact that by

passing fluids under compression through the valve 47 and to a position upon the opposite side of the valve a hydrostatic action is produced against the upper end of the valve unit with a constant differential.

It will also be evident that due to the use of the main valve assembly here shown with its hollow valve member 47 the various sections of the tool will be sealed off at atmospheric pressure and a by-pass of air compressed by hydrostatic pressure will be admitted into the bottom section to cause the fluid to rise to the face of the valve and for the purpose of by-passing air under compression as a means to blow away and to prevent the entry of sand, etc., into the mechanical apparatus in a manner that might disturb the normal mechanical function of the valve assembly.

Attention is also directed to the fact that fluid may be by-passed through the shell 32 and around 20 and along the sleeve 36 and its tubular stem 35 so that the valve assembly and the shell may readily telescope during their operation without resistance from the compression which might be created by entrapped fluid within the device.

In operation of the tool it will, of course, be evident that the active hydrostatic pressure created will be in direct proportion to the submergence of the tool within the fluid or liquid concerned. Attention is also directed to the fact that when the well bottom has been reached and the valve structure has been opened the great difference in pressure between the inside and outside of the tool will cause the fluids and extraneous matter to surge into the barrel 16 and upwardly around the valve to the upper section 14, and in so doing will have the action of drawing in entrained and suspended solids to be entrapped above the flapper valve 67, thus making it possible to bring about the recovery of a relatively 35 large volume of solid material and materials in relatively large pieces. In fact, by varying the size and construction of the shoe 62 it is possible to recover other things than sand and silt, such for example, as broken machine parts, drill cutters, and the like, which might have been lost in the bore.

It will thus be seen that the bailer here disclosed, while decidedly simple in construction and operation as compared with other devices of this 50 character, is portable, readily adapted for use under varying conditions such as the deviation of bores beneath the earth's surface, which in the present instance insures that the device will not accidentally actuate, and which may be readily 55 controlled and operated at any desirable point.

While I have shown the preferred form of my invention, as now known to me, it will be understood that various changes may be made in combination, construction, and arrangement of 60 parts by those skilled in the art without departing from the spirit of my invention as claimed.

Having thus described my invention, what I claim and desire to secure by Letters Patent is:

1. A bailer comprising an upper tubular member, a valve chamber formed in the lower end thereof, a valve section into which said upper tubular member telescopes, means adjacent the lower end thereof to limit the downward movement of said upper tubular member with relation to the valve section, means for limiting the upward movement of the tubular member with relation to the valve section, yieldable means normally holding said tubular member in its uppermost position with relation to said section, a valve unit 70

mounted for free longitudinal movement within the valve chamber of the upper tubular section, said unit comprising a valve cylinder open at its lower end and formed with laterally extending 5 ribs spacing it from the wall of the valve chamber, a valve member therebeneath and having a cylindrical stem adapted to reciprocate within the valve cylinder and to form a fluid seal with relation thereto, yieldable means within the cylinder for holding said valve in its lowermost position, a valve seat substantially closing the lower ends of the valve chamber of the upper tubular member and upon which seat the valve normally 10 rests, and means disposed in the longitudinal path of travel of the valve within the tubular valve section to be engaged by the valve whereby it will be lifted from its seat.

2. A bailer comprising an upper tubular member, a valve chamber formed in the lower end 20 thereof, a valve section into which said upper tubular member telescopes, means adjacent the lower end thereof to limit the downward movement of said upper tubular member with relation to the valve section, means for limiting the upward movement of the tubular member with relation to the valve section, yieldable means normally holding said tubular member in its uppermost position with relation to said section, a valve unit mounted for free longitudinal movement 30 within the valve chamber of the upper tubular section, said unit comprising a valve cylinder open at its lower end and formed with laterally extending ribs spacing it from the wall of the valve chamber, a valve member therebeneath and having a cylindrical stem adapted to reciprocate within the valve cylinder and to form a fluid seal with relation thereto, yieldable means within the cylinder for holding said valve in its lowermost position, a valve seat substantially closing the 35 lower ends of the valve chamber of the upper tubular member and upon which seat the valve normally rests, means disposed in the longitudinal path of travel of the valve within the tubular valve section to be engaged by the valve whereby it will be lifted from its seat, a barrel connected with the lower end of said tubular valve section and a check valve carried at the lower end thereof to permit the entry of fluid to the barrel.

3. A bailer comprising an upper tubular section 50 adapted to receive a fluid, a valve member yieldably mounted at the upper end of said section adapted to operate under a predetermined pressure, a tube extending downwardly into said section and open at its lower end, the upper end 55 of said tube communicating with said valve member whereby a fluid seal will be produced within the tubular section when the fluid therein has reached a level above the lower open end of the tube, a tubular valve section into which said upper tubular section telescopes, means yieldably holding said sections in distended relation to each other, the lower end of the upper tubular section being formed with a valve structure receiving 60 compartment in communication with the upper section, a valve sleeve disposed within said compartment, a valve member having a stem reciprocably mounted within said sleeve, the sleeve being closed at its upper end, a spring within the sleeve yieldably holding the stem in its lowermost position, a valve seat rigidly carried by the upper tubular section and onto which seat 65 said valve is yieldably held by the spring, the valve and stem being formed with a by-pass passageway opening outwardly at a line below the 70 point of contact of the valve with its seat and on

the interior of the valve sleeve at a point on the upper end of the stem whereby the valve will have a fluid balance, a lower tubular barrel section rigidly secured to the tubular valve section, a valve at the bottom thereof yieldable in response to external pressure and adapted to be closed by fluid within the tubular section to entrap the same, and means for lifting the balanced valve from its seat after a predetermined relative movement of the upper tubular section with respect 10 to said tubular valve section and said lower tubular barrel section.

4. In a bailer adapted to operate under hydrostatic pressure, a valve unit comprising a housing, a valve seat rigidly secured at the lower end 15 thereof, a valve sleeve within the housing closed at its upper end and around which fluid may pass through the housing, a valve adapted to rest upon the valve seat and having its stem extending into said sleeve, said valve and sleeve 20 having a tight sliding fit with relation to each other, a by-pass opening through the valve and its stem from a point below the line of contact of the valve with the seat to a point interiorly of the sleeve, and a spring within the sleeve normally holding the valve on its seat.

5. A bailer comprising an upper tubular section suspended from a suitable member and normally closed at its upper end, a tubular valve section in longitudinal alignment therewith and movable relative thereto, a valve within said tubular valve section balanced by the fluid within the bailer, a cylindrical barrel section in longitudinal alignment with the tubular valve section disposed therebeneath and in communication therewith, a flapper valve member near the bottom of the barrel section and through which fluid may flow under hydrostatic pressure into the barrel, means whereby the hydrostatic pressure of said fluid will balance the balanced valve within the 40 tubular valve section, and means for opening said balanced valve upon relative downward movement of said upper tubular section with relation to said tubular valve section to permit the fluid under hydrostatic pressure within the 45 barrel section to surge upwardly past said balanced valve and into said upper tubular section there to be entrapped.

6. A bailer comprising an upper tubular section suspended from a suitable member and normally 50 closed at its upper end, a tubular valve section in longitudinal alignment therewith and movable relative thereto, a valve structure having limited vertical movement within said tubular valve section including a balanced valve, a cylindrical barrel section in longitudinal alignment with said tubular valve section disposed therebeneath and in communication therewith, a flapper 55 valve member near the bottom of said barrel section and through which fluid may flow under hydrostatic pressure into said barrel, means whereby the hydrostatic pressure of said fluid will balance said balanced valve in said tubular valve section, means for opening said balanced valve upon a predetermined relative downward movement of said upper tubular section with relation to said barrel section to permit the fluid under hydrostatic pressure within said barrel section to surge upwardly past said balanced valve and into 60 said upper tubular section there to be entrapped, and means for closing said balanced valve upon upward relative movement between said upper tubular section and said tubular valve section to 65 entrap fluid under hydrostatic pressure within said upper tubular section.

7. A bailer comprising an upper tubular section suspended from a suitable member and normally closed at its upper end, a tubular valve section in longitudinal alignment therewith and movable relative thereto, a valve structure having limited vertical movement within said tubular valve section including a balanced valve, a barrel section in longitudinal alignment with said tubular valve section disposed therebeneath and in communication therewith, a flapper valve member near the bottom of said barrel section and through which fluid may flow under hydro-static pressure into said barrel section, means whereby the hydro-static pressure of the fluid will balance said balanced valve in said tubular valve section, means for opening said balanced valve after a predetermined relative downward movement of said upper tubular section with relation to said barrel section to permit the fluid under hydro-static pressure within said barrel section to surge upwardly past the balanced valve and into said upper tubular section there to be entrapped, and means for permitting the entrapped fluid within the bailer to be expelled from said barrel when the bailer has been removed from the well.
8. A bailer comprising an upper tubular section suspended from a suitable member, a tubular valve section in longitudinal alignment therewith and movable relative thereto, a balanced valve mounted for limited vertical movement within said tubular valve section, a barrel section in longitudinal alignment with said tubular valve section disposed therebeneath and in communication therewith, a flapper valve member near the bottom of said barrel section and through which fluid may flow under hydro-static pressure into said barrel section, means whereby the hydro-static pressure of said fluid will balance said balanced valve in said tubular valve section, means for opening said balanced valve upon relative downward movement of said upper tubular section with relation to said barrel section to permit the fluid under hydro-static pressure within said barrel section to surge upwardly past said balanced valve and into said upper tubular section there to be entrapped, means for permitting the entrapped fluid within the bailer to be expelled from said barrel section when the bailer has been removed from the well, and means for entrapping fluid under pressure in said upper tubular section to be utilized in expelling the fluid from said barrel section when the bailer is being emptied.
9. A bailer comprising a tubular valve section, an upper tubular section including a valve sleeve telescoping into said tubular valve section, yieldable means normally holding said upper tubular section and said tubular valve section in distended relation with respect to one another, a valve unit mounted within the lower end of said valve sleeve including a valve member and a cushion cylinder, said valve member being mounted within said cushion cylinder and having a sealed slid-
- able fit therewith, yieldable means within said cushion cylinder to hold said valve member in its outermost position in relation thereto, a valve seat carried by said valve sleeve and against which said valve member normally seats, means for limiting upward movement of said valve sleeve with relation to said tubular valve section, and means at the lower end of said tubular valve section to be encountered by said valve member in its movement for lifting said valve member from its seat against the tension of said spring within said cushion cylinder.
10. A bailer comprising a tubular valve section, an upper tubular section including a valve sleeve telescoping into said tubular valve section, yieldable means normally holding said upper tubular section and said tubular valve section in distended relation with respect to one another, a valve unit mounted in the lower end of said valve sleeve including a valve member and a cushion cylinder, said valve member being mounted within said cushion cylinder and having a sealed slideable seat therewith, yieldable means within said cushion cylinder for holding said valve member in its outermost position with relation thereto, a valve seat carried by said valve sleeve and against which said valve member normally seats, means for limiting upward movement of said valve sleeve with respect to said tubular valve section, means at the lower end of said tubular valve section to be encountered by said valve member in its movement for lifting said valve member from its seat against the tension of said spring within said cushion cylinder, and a by-pass duct through said valve member from a point below its seat to a point within said cushion cylinder for permitting fluid to pass into said cushion cylinder to balance said valve member.
11. In a suction bailer, an upper tubular section defining an air-tight chamber, a lower tubular barrel section defining a sand chamber, means for controlling communication between said chambers including a valve seat and a valve member mounted to engage said seat from above, and means for balancing said valve when the same is closed with fluid pressure from said sand chamber.
12. In a suction bailer, an upper tubular section defining an air-tight chamber, a lower tubular barrel section defining a sand chamber, means for controlling communication between said chambers including a valve seat and a valve member adapted to engage said seat from above, said valve member including a valve stem extending above the same, a sealed chamber mounted above said valve and within which said stem is adapted to move, and a port extending through said valve member from below said seat for passage of fluid from said sand chamber to said sealed chamber above said valve to balance said valve when the same is in engagement with its seat.

ELMER R. SMITH.
